Primary Examiner—Charles A. Rademaker*Attorney, Agent, or Firm*—Basil Travis**[57] CLAIM**

The ornamental design for a rotatable skipping toy, as shown and described.

DESCRIPTION

FIG. 1 is a perspective view of a rotatable skipping toy showing my new design; and,

FIG. 2 is a side perspective view thereof shown in an inverted position.

The broken line showing of a human figure in FIG. 1 is for illustrative purposes only and forms no part of the claimed design.
